UNITED STATES PATENT OFFICE

THOMAS C. CRAVEN, OF DUMONT, NEW JERSEY

CLOSURE FOR LOCOMOTIVE CAB WINDOWS

Application filed August 22, 1931. Serial No. 558,786.

The present invention relates to new and useful improvements in window closures, and more particularly to a window closure especially adapted for use in the windows of locomotive cabs.

It is one of the objects of the invention to provide a cab window closure for use in stormy or inclement weather.

It is a further object of the invention to provide a device of the aforementioned character which will provide clear vision for the engineer when in operative position.

It is a still further object of the invention to provide a window closure which may be readily secured in operative position without the use of separate fastening elements.

A still further object of the invention resides in the provision of a window closure which may be readily attached to and removed from the window opening in connection with which it is used.

A still further object of the invention resides in a novel arrangement of parts whereby the window closure may be employed and at the same time provides ample ventilation for the interior of the locomotive cab.

With the above and other objects in view, reference will be had to the accompanying drawings, wherein—

Figure 1 is a perspective view of the forward end of an electric locomotive showing a device constructed in accordance with the present invention in place in one of the cab windows thereof,

Figure 2 is a perspective view of the window closure,

Figure 3 is a view in elevation showing the interior of the window opening closure,

Figure 4 is a vertical sectional view taken on a line extending substantially centrally of the window closure,

Figure 5 is a horizontal sectional view of the closure in its operative position,

Figure 6 is an end view showing the closure member in its folded position, and

Figure 7 is a partially broken away longitudinal sectional view illustrating the closure member in folded position.

Referring more particularly to the draw-

ings, the device comprises a main frame member 10 which is provided with a window or similar opening 11. Side members 12 are hingedly connected to the frame member 10 as at 13, and are adapted to fold inwardly thereof. There are two of these side members, and each is formed with a channel or the like 14 extending along its free edge which channel is adapted to receive its respective side edge of the cab window opening in which the device is to be placed as illustrated at 15 in Figure 5 of the drawings. When the side members 12 are folded inwardly of the main frame member 10 as illustrated in Figure 6, they are retained in this position by means of clips or like 16 which are pivotally mounted at 17 and are adapted to swing about their pivotal points into engagement with the side members and out of engagement therewith to permit of swinging outwardly as illustrated in Figure 3 of the drawings. The side members 12 are each provided with a window opening or the like 17, and ventilating openings or the like 18 may also be provided in these members, if desired. A rain shed 19, preferably in the form of an angle iron may extend along the upper portion of the main frame member 10, and similar members 20 may be employed over the windows 17 of the side members if desired.

A bottom end member 21 is hingedly connected as at 22 to the main frame member 10, see Figure 4, and this bottom member 21 is formed on its under face with a channel 23 which receives the film 24 of the locomotive cab window opening. This bottom member 21 may be provided with an opening 25 adapted to be closed by a sliding closure member 26 and this opening provides for ample ventilation of the interior of the closure member.

As best illustrated in Figure 4, a top end wall such as 30 is provided. This top end wall has a depending flange 31 and an extending outer edge portion 32 which overlies the top edge of the main frame member 10. The inner upper edge of the member 30 is extended inwardly of the cab window open-

ing as indicated at 33 in said figure. The upper edge of the cab window opening is designated 34. The inner face of the main frame member 10 is provided with a handle 35 to aid in the placement and detachment of the device in and from operative position and as best illustrated in Figure 4, the openings 18 may be controlled by sliding valve or plate members 37 to determine the extent to which they are opened and consequently the amount of air admitted to the interior of the device thereby.

In Figure 7 the device is illustrated in its folded position in which position the device 15 may be transported readily from one location to another. In folding of the device, the side members 12 are folded inwardly and the clips 16 heretofore mentioned are moved into engagement with the side members to 20 hold them in their inwardly folded position after which the lower end member is folded upwardly as illustrated in full lines in said Figure 7 about its hinges 22.

When it is desired to place the device in 25 position in a locomotive cab window, the lower end member 21 is folded downwardly and the side members folded outwardly after which the member 21 is again folded upwardly. The side members 12 are now engaged with the side edges of the window opening, the said side edges being received in the channels 14 of the side members as 30 illustrated in Figure 5. After this has been done, the end member is folded to its downward position in which it is shown in dotted lines in Figure 7 and its ends engage the side members near their lower ends and thus prevent movement of the side members 35 about their hinges 13 and prevent their becoming disengaged with the side edges of the window opening, thus holding the device in place without employing separate fastening means. The top wall 30 may or may not be placed in position as desired, and when 40 not employed, permits of greater ventilation of the interior of the device.

From the foregoing it will be apparent 45 that the present invention provides a new and novel device of the character set forth 50 in which all of the objects of the invention are carried out in a highly efficient manner.

While the invention has herein been disclosed in a preferred form, it is to be understood 55 that the invention is not to be limited to the specific construction herein illustrated, and that it may be practiced in other forms without departing from the spirit thereof.

Having thus described the invention, what 60 I claim as new and desire to secure by Letters Patent is:—

In a closure for window openings, a main frame member, sides hinged to the vertical edges of said main frame member and having the inner longitudinal edge portions 65 thereof provided with channels for the snug

reception of the vertical edge portions of the walls of a window opening, a bottom member hinged to the main frame and movable into engagement with the side members, and means carried by said bottom member for engagement with the bottom of the window opening to aid in securing the closure in position.

In testimony whereof I affix my signature.

THOMAS C. CRAVEN.
